(57) CLAIM

The ornamental design for a drumstick pouch, as shown and described.

DESCRIPTION

FIG. 1 is a front elevational view of the drumstick pouch embodying my new design,

FIG. 2 is a rear elevational view thereof,

FIG. 3 is a right side view thereof,

FIG. 4 is a left side view thereof,

FIG. 5 is a top view thereof,

FIG. 6 is a bottom view thereof; and,

FIG. 7 is a front perspective view of the drumstick pouch, the pair of drumsticks within the pouch shown in phantom comprising no part of the present invention.
